S. H. YANCEY

SEAL FOR METAL CANS AND LIKE CONTAINERS

Filed April 13, 1922

FIG. 1.

FIG. 2.

FIG. 4.

Inventor
S. H. Yancey.

By *Attwells, Jr.* Attorney

UNITED STATES PATENT OFFICE.

SAMUEL H. YANCEY, OF NEW YORK, N. Y.

SEAL FOR METAL CANS AND LIKE CONTAINERS.

Application filed April 13, 1922. Serial No. 552,125.

To all whom it may concern:

Be it known that I, SAMUEL H. YANCEY, a citizen of the United States, residing at New York city, in the county of New York and State of New York, have invented certain new and useful Improvements in Seals for Metal Cans and like Containers; and I do hereby declare the following to be a full, clear, and exact description of the invention, such as will enable others skilled in the art to which it appertains to make and use the same.

The primary object of the present invention is the provision of means for sealing shipping cans, and which will admit of the subsequent closing of the cans by an ordinary stopper after the seal has been broken.

The can or analogous container is provided with an opening through which the same is filled and the contents subsequently drawn off. A collar, formed with the can, projects therefrom in line with the opening and has its inner wall grooved. The closure consists of a metal cap of such relative size as to fit snugly within the collar, a portion of the rim or wall of the cap being pressed outwardly into the groove formed in the inner wall of the collar, whereby to prevent displacement of the closure and making it necessary to cut the crown of the cap when it is required to gain access to the contents of the can.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a sectional view of the top of a can or container sealed in accordance with the present invention,

Figure 2 is a view similar to Figure 1, with the closure in position and prior to

pressing a portion thereof outwardly into the groove of the collar,

Figure 3 is a sectional perspective view, the closure being omitted, and

Figure 4 is a view similar to Figure 1 of 55 a modification.

Corresponding and like parts are referred to in the following description and designated in the several views of the drawings by like reference characters.

The numeral 1 designates the top of a sheet metal or other container in which is formed an opening 2, through which the container is filled and the contents subsequently drawn off. A collar 3 pressed outwardly from the top of the can or container in line with the opening 2 therein may be of any construction. A groove 4 is provided in the inner wall of the collar 3 and extends entirely there around.

The closure for sealing the can or container preferably consists of a sheet metal cap which comprises a crown 5, a wall or rim 6 and an outer flange 7. The closure is of a size to snugly fit within the collar 3 and after being positioned therein, a portion of the wall or rim 6 is pressed outwardly into the groove 4, as indicated at 8, thereby preventing removal of the closure and assuring a tight joint. The outer flange 7 engages the upper edge of the collar 3, thereby limiting the inward movement of the closure

when pressed into the collar and assisting materially in preserving a close joint and stiffening the closure to prevent its removal.

The groove 4 may be at any point in the depth of the collar and, as shown in Figure 4, the groove 4 is located at the inner end of the collar 3 and in the remaining views at a point between the inner and outer ends 80 of the collar.

To open a can or container which has been sealed in accordance with the present invention, it is necessary to cut away the crown 5 of the closure. The can may be 85 subsequently closed by means of an ordinary stopper which may be inserted in the collar 3, or by means of a screw cap which may be fitted to the threaded collar 9, as will be readily understood. The pressing of the 100

part 8 of the closure outwardly into the groove 4 may be effected by a beading tool, such as commonly used for expanding the ends of pipes in the head and crown sheet 5 of boilers, or in any preferred way.

What is claimed is:

A container having a collar about its filling and dispensing opening, a closure for said collar, the closure being of a shape to 10 permit application of a stopper after puncture of the closure, said collar at its outer

end having an outwardly extending flange, and a collar for fastening of a closure thereto surrounding the first collar and having an inwardly extending flange overlapped by 15 the said flange.

In testimony whereof I affix my signature in presence of two witnesses.

SAMUEL H. YANCEY.

Witnesses:

ANNA J. MARRON,
EDITH G. MARTIN.
